FIG. 4

INVENTOR:

George A. Stein

HIS ATTORNEY

UNITED STATES PATENT OFFICE.

GEORGE A. SEIB, OF ILION, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 912,186.

Specification of Letters Patent.

Patented Feb. 9, 1909.

Application filed September 23, 1908. Serial No. 454,357.

To all whom it may concern:

Be it known that I, GEORGE A. SEIB, citizen of the United States, and resident of Ilion, in the county of Herkimer and State of New York, have invented certain new and useful Improvements in Type-Writing Machines, of which the following is a specification.

My invention relates to typewriting machines and more particularly to means for effecting a release of the platen scale when the feed rollers are released and the object of said invention is to provide simple and efficient means of the character specified.

To the above and other ends which will hereinafter appear, my invention consists in the features of construction, arrangements of parts and combinations of devices to be hereinafter described and particularly pointed out in the appended claims.

In the accompanying drawings wherein like reference characters indicate corresponding parts in the various views, Figure 1 is an end elevation partly in section of a typewriter carriage equipped with the devices of my invention, the parts in this view being shown in normal position. Fig. 2 is a like view of the same with some of the parts omitted, this view illustrating the disposition of the parts when the feed rollers are released. Fig. 3 is a top view of the carriage with the platen omitted and parts broken away. Fig. 4 is an enlarged detail perspective view of a device forming part of the means for supporting the platen scale. Fig. 5 is an enlarged detail bottom view showing the means for effecting an adjustment of the bearing of a pivoted transmitting device to be hereinafter more fully described.

I have shown my invention in the present instance applied to a Monarch machine but it should be understood that the invention may be embodied in other styles of machines.

The platen frame or carriage comprises a rear cross or traverse bar 1 grooved on opposite sides at 2 for coöperation with anti-friction balls or rollers which are likewise received in grooved fixed guide rails (not shown). Projecting forwardly from the traverse bar are end plates 3 which are provided with bearing openings for a platen shaft 4 which supports a rotative platen 5. Ears 6 are formed upon the traverse bar and extend forwardly therefrom. These ears receive feed roll hangers 7 pivoted at 8 to said ears.

Springs 9 are coiled at one end portion as at 10 around the pivots 8 and each bears at one end as at 11 against the traverse bar and bears at the opposite end 12 against the under side of the associated hanger to press it towards the platen. A feed roll shaft 13 is connected at its ends to the hanger arms 7 and supports independently movable main paper feed rollers 14 which are spaced apart by sleeves 15 which surround the shaft 13. The hanger arms 7 extend downwardly beyond the shaft 13 and carry anti-friction rollers 16 for purposes which will hereinafter appear. A rock shaft 17 is mounted in the end plates 3 of the carriage and projects beyond the left-hand end plate and carries at its extended end a finger piece 18 by which the rock shaft may be controlled. Stop pins 19 and 20 project outwardly from the left-hand end plate 3 on opposite sides of the finger piece or crank arm 18 in order to limit its movement in opposite directions. A paper apron 21 is bent to conform substantially to the curvature of the platen and is provided with ears 22 at the upper rear side thereof. These ears loosely surround the rock shaft 17 so as to pivotally connect the paper apron to the rock shaft. Feed roll hangers 23 are likewise pivoted to the ears 6 as indicated at 24. Springs 25 are each coiled at one end portion around one of the pivots 24 and each bears at 26 against the traverse bar 1. The opposite end of each spring bears against the bottom of the associated hanger arm 23. The forward ends of the hangers 23 support a shaft 27 for the forward set of feed rollers 28 which are spaced apart on the shaft by spacing sleeves 29. The hanger arms 23 are situated directly beneath the hanger arms 7 so that the anti-friction rollers 16 bear on the upper sides of the hanger arms 23 and force the hanger arms 23 downwardly to move the forward set of feed rolls away from the platen when the hanger arms 7 are moved away from the platen. The hanger arms 23 have leaf springs 31 riveted thereto at 32, the free ends of said leaf springs bearing upwardly against the forward end portion of the paper apron to maintain it in operative position bearing against the platen. When the hanger arms 7 and 23 are lowered the springs 31 will likewise be lowered, thus freeing the paper apron from pressure and allowing the paper apron to drop away from the face of the platen.

Lugs 33 extend forwardly from the traverse bar 1 and form supports for rigid bracket arms 34 which are secured to the lugs by screws 35. The forward ends of these bracket arms are struck up to form ears 36. Each pair of these ears receives between them a device 37 which may be of the form shown in detail in Fig. 4. This device is provided with ears 38 received between the ears 36 and apertured to receive a pivot 39 which pivotally connects the device to the bracket arm. The arm 40 of each of the devices 37 provides means for connecting a platen scale 41 thereto by riveting the devices and platen scale together as at 42. A leaf spring 43 is connected to each bracket arm 34 by a rivet 44 and bears at its free end against a portion 45 of the associated pivoted device 37, the tension of the spring tending 20 to turn the platen scale about the pivots 39 so as to press the upper edge of said scale against the platen.

One or both of the pivoted devices 37 may be provided with an off-set and rearwardly 25 extending arm 46. In the present instance I have shown but one of the devices provided with this off-set arm, that being the one at the right-hand end of the platen. This arm 46 cooperates with a crank arm 47 formed as a part of a rock shaft 48 received in a bearing 49. A crank arm 50 likewise projects from the rock shaft 48 and is bent inwardly at its free end to form a finger 51 which is received beneath the right-hand hanger arm 7 of the main paper feed rollers. The bearing 49 for the pivoted actuating device 47-48-50, is adjustably secured to the bottom of the right-hand bracket 34 by headed screws 52 which pass through slots 53 in the bearing in order to afford an adjustment of the bearing and the pivoted device carried thereby fore and aft of the machine. The effect of this adjustment is to vary the extent of throw transmitted to the platen 45 scale through an actuation of the pivoted device 47-48-50. It may be found desirable to provide one of these pivoted devices at each end of the platen to cooperate with each of the devices 37, but in most instances 50 (especially where a short platen is employed) one of the devices will be found sufficient. When the parts are in normal position as shown in Fig. 1 the feed rollers, paper apron and platen scale are adjacent to or bear 55 against the face of the platen under the pressure of the various springs which control the parts. When, however, the finger piece 18 is moved to the position shown in Fig. 2 it is effective to turn the rock shaft 17 to bring 60 the projections or studs 54 into contact with the hanger arms 7, thus forcing the arms downwardly around the pivots 8. The effect of this movement is to transmit motion to the hanger arms 23, thus moving the 65 forward set of feed rollers away from the

platen and releasing pressure on the paper apron which is free to drop away from the platen. This same movement of the hanger arms 7 effects a vibration of the pivoted device 47-48-50, causing the arm 47 thereof 70 to turn the right-hand device 37 to effect a movement of the platen scale around the pivots 39 to the position shown in Fig. 2, thus relieving all of the paper feeding and controlling devices from pressure and releasing them from contact with the platen. As hereinbefore pointed out an adjustment of the pivoted device 47-48-50 is effective to vary the throw of the platen scale.

While I have referred herein to the part 41 80 as a platen scale, the term usually employed to designate this part, it is not in all instances provided with a scale and I do not mean necessarily that it should be provided with a scale.

What I claim as new and desire to secure by Letters Patent, is:—

1. In a typewriting machine, the combination of a platen, feed rollers, a platen scale, means for releasing the feed rollers and for 90 simultaneously moving said scale away from the platen, and adjustable means whereby the extent of movement of said scale may be regulated.

2. In a typewriting machine, the combination of a platen, feed rollers, a paper apron, a platen scale, means for concurrently effecting a movement of the feed rollers, paper apron and platen scale away from the platen, and adjustable means whereby the extent of movement of said scale may be regulated.

3. In a typewriting machine, the combination of a platen, rear main paper feed rollers, forward paper feed rollers, a paper apron, a platen scale, means for concurrently moving all of said paper feed rollers, said paper apron and said platen scale away from the platen, and adjustable means for varying the extent of movement of the platen scale.

4. In a typewriting machine, the combination of a platen, paper feed devices, means for releasing said paper feed devices, a pivoted platen scale, means for moving the platen scale away from the platen when the paper feed devices are released, said moving 110 means comprising a pivoted device actuated by said releasing means and actuating said pivoted platen scale, and means for effecting an adjustment of certain of said parts to vary the throw of the platen scale.

5. In a typewriting machine, the combination of a platen, paper feed devices, means for releasing said paper feed devices, a pivoted platen scale, means for moving the platen scale away from the platen when the paper feed devices are released, said moving 125 means comprising a pivoted device actuated by said releasing means and actuating said pivoted platen scale, and means for effecting an adjustment of said pivoted device.

6. In a typewriting machine, the combination of a platen, paper feed devices, means for releasing said paper feed devices, a pivoted platen scale, and means for moving the platen scale away from the platen when the paper feed devices are released, said moving means comprising a pivoted device having one arm which co-acts with said releasing means to be actuated thereby and another arm which co-acts with the platen scale to move it. 45
7. In a typewriting machine, the combination of a platen, paper feed devices, means for releasing said paper feed devices, a pivoted platen scale, and means for moving the platen scale away from the platen when the paper feed devices are released, said moving means comprising a pivoted device having one arm which co-acts with said releasing means to be actuated thereby and another arm which co-acts with the platen scale to move it, and means whereby an adjustment of said pivoted device may be effected. 50
8. In a typewriting machine, the combination of a platen, paper feed devices, means for releasing said paper feed devices, a pivoted platen scale, and means for moving the platen scale away from the platen when the paper feed devices are released, said moving means comprising a rock shaft having two crank arms, one of said arms co-acting with said releasing means and the other of said arms co-acting with the platen scale. 55
9. In a typewriting machine, the combination of a platen, paper feed devices, means for releasing said paper feed devices, a pivoted platen scale, means for moving the platen scale away from the platen when the paper feed devices are released, said moving means comprising a rock shaft having two 60
- crank arms, one of said arms co-acting with said releasing means and the other of said arms co-acting with the platen scale, a bearing for said rock shaft, and means for effecting an adjustment of said bearing. 65
10. In a typewriting machine, the combination of a platen, paper feed rollers, hangers therefor, means for actuating said hangers to release the feed rollers, a movable platen scale, a pivoted device co-acting with a feed roll hanger to be actuated thereby and co-acting with the platen scale to move it, and means for effecting an adjustment of certain of said parts to vary the throw of the platen scale. 70
11. In a typewriting machine, the combination of a platen, paper feed rollers, hangers therefor, means for actuating said hangers to release the feed rollers, a movable platen scale, and a rock shaft having two crank arms, one of said crank arms co-acting with a feed roll hanger to effect an actuation of the rock shaft and the other of said arms co-acting with said platen scale to move it. 75
12. In a typewriting machine, the combination of a platen, paper feed rollers, hangers therefor, means for actuating said hangers to release the feed rollers, a movable platen scale, a rock shaft having two crank arms, one of said crank arms co-acting with a feed roll hanger to effect an actuation of the rock shaft and the other of said arms co-acting with said platen scale to move it, a bearing for said rock shaft, and means whereby an adjustment of said bearing may be effected. 80
